[57] CLAIM

The ornamental design for a shrub clipping catcher, as shown and described.

DESCRIPTION

FIG. 1 is a top, front and left side perspective view of the shrub clipping catcher showing our new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken-line disclosure of a portion of a tree and additional catcher shown in FIG. 1 is for illustrative purposes only and forms no part of the claimed design.
